UNITED STATES PATENT OFFICE

148,267

DESIGN FOR A PICTURE FRAME BORDER MAT OR SIMILAR ARTICLE

Joseph Amaru, Somerville, Mass.

Application August 14, 1947, Serial No. 140,861

Term of patent 14 years

(Cl. D29—20)

To all whom it may concern:

Be it known that I, Joseph Amaru, a citizen of the United States, residing at Somerville, in the county of Middlesex, in the Commonwealth of Massachusetts, have invented a new, original, and ornamental Design for a Picture Frame Border Mat or Similar Article, of which the following is a specification, reference being had to the accompanying drawing, forming a part thereof, in which:

I claim:

The ornamental design for a picture frame border mat or similar article, substantially as shown.

JOSEPH AMARU.
